UNITED STATES PATENT OFFICE.

JOHN M. GAAR, OF RICHMOND, INDIANA, ASSIGNOR TO GAAR, SCOTT & COMPANY, OF SAME PLACE.

STRAW-STACKER.

SPECIFICATION forming part of Letters Patent No. 325,526, dated September 1, 1885.

Application filed June 18, 1885. (No model.)

To all whom it may concern:

Be it known that I, JOHN M. GAAR, a citizen of the United States, residing at Richmond, in the county of Wayne and State of Indiana, have invented new and useful Improvements in Straw-Stackers, of which the following is a specification.

This invention relates to that class of straw-stackers which receive the straw from the threshing-machine, and in which the straw-carrier or conveyer-trough is capable of swinging horizontally about a fixed center or pivot and thereby distributes the straw over a semi-circular area.

15 The object of my invention is to simplify and make more convenient and durable the various parts of a straw-stacking machine, whereby the straw-carrier can be raised and lowered with facility and turned to any desired position or angle with relation to the main frame of the machine without interrupting the progress of the work.

25 My invention consists in certain peculiarities in the construction and combination of devices for raising and lowering the straw-stack, for turning it to any desired position and holding it steady at any required angle with the main frame, and for folding it compactly for transportation, all of which will be 30 hereinafter more fully set forth.

35 In the annexed drawings, illustrating my invention, Figure 1 is a perspective view of my improved straw-stacking machine, showing the conveyer-trough extended and turned at an angle with the main frame. Fig. 2 is a 40 side elevation of the stacker mounted on trucks and folded for transportation on the road. Figs. 3 and 4 are detail views, partly in section.

45 The main frame of the machine, which is designated by the numeral 1, may be made in any suitable or convenient form, and is preferably mounted on trucks to facilitate transportation. This main frame comprises the side rails or sills, 2 2, which, together with their connecting cross-pieces 3, serve as a support for the operative mechanism of the stacker.

50 To the sills 2 2 is pivoted a gear-frame, 4, in which is journaled the driving-shaft 5, and also the lower end of the king-bolt 6, that

forms a pivot for the extended conveyer-trough in turning laterally to any desired angle with the main frame.

Above the main frame 1, and secured to its sills 2 2 and to one of the cross-pieces 3, is a 55 ring, 7, preferably formed of T-iron, as shown. This circle serves as a brace or stay and also as a brake for the stacker or conveyer to hold it at any desired angle with the main frame and prevent it from being blown from side to 50 side, as will be presently described.

Mounted loosely on the king-bolt 6, above the circle 7, is a yoke, 8, the upper end of which is attached to and supports a bolster, 9, that is centrally pivoted on the upper end of 65 the king-bolt. The bolster 9 carries at its ends the arms 10 10, that support the pivoted end of the conveyer-trough 11. These arms 10 10 are provided with flanged guide-lugs 12 12, for supporting the segment-racks 13 13 in 70 operative relation with their actuating-pinions 14 14, the latter being rigidly secured to the opposite ends of a shaft, 15, which is provided centrally with suitable bearings, 16 16, that are secured to the bolster 9, as shown in Fig. 1. 75

The shaft 15 is provided with a spur-gear, 17, that is actuated by a worm-shaft, 18, having a crank-handle, 19, by turning which the conveyer-trough 11 can be raised or lowered at will to any desired position.

80 The conveyer-trough 11 may be made in the usual form with folding sections for convenience in transportation, and is provided with the ordinary canvas side guards, 20 20, and with a traveling apron, 21, that is passed over 85 rollers 22 at the ends of the trough, one of said rollers having a shaft, 23, which carries a sprocket-wheel, 24, that is connected by a chain, 25, to a shaft, 26, which is journaled in bearings 27, attached to the under side of the 90 bolster 9. The shaft 26 extends only about half the length of the bolster 9, and is provided at its inner end with a bevel-pinion, 28, which meshes with a loose bevel-gear, 29, on the king-bolt 6, which loose gear 29 in turn 95 meshes with a bevel-pinion, 30, on the inner end of a shaft, 31, that is mounted in bearings 32 on the circle 7, or other fixed support.

To the outer end of the shaft 31 is fixed a sprocket-wheel, 33, that is connected by a 98

chain, 34, to a similar sprocket-wheel, 35, on the driving-shaft 5, which is provided with a driving-pulley, 36, that receives power by suitable belting from a pulley on the thrashing-machine, or from any other convenient source.

By power applied to the driving-pulley 36 the conveyer-apron 21 will be actuated continuously, through the intermediate mechanism, so as to carry the straw through the conveyer-trough 11, the latter being meanwhile capable of turning or swinging horizontally to any desired angle with the main frame for the purpose of distributing the straw over the stack as required.

It is obvious that the conveyer-trough 11 can be readily turned from side to side, together with the bolster 9 and supporting-arms 10 10, by reason of the flexible connection of the shafts 26 and 31 through the bevel-gears 28 29 30, one of said shafts, as 31, being mounted in fixed bearings, so as to maintain its connection with the driving-shaft, while the shaft 26 is journaled in bearings attached to the bolster 9, so as to be capable of turning therewith.

The supporting-arms 10 10 are connected by adjustable chains 37 to a friction clamp or shoe, 38, that is capable of sliding on the flanged surface of the circle 7 as the bolster 9 and superimposed parts are swung horizontally during the operation of stacking, the circle 7 and shoe 38 thus serving as a brake to steady the conveyer and its supports while the machine is in use.

A movable dog or brace, 39, is pivoted to the main frame 1, and has its upper end so formed as to be capable of fitting against one side of a beveled shoulder, 40, on the upper part of the tilting frame 4, a stationary brace, 41, being arranged on the opposite side from the movable dog 39, and acting in conjunction therewith to steady the stacker when elevated.

The conveyer-trough 11 or stacker proper is raised and lowered by the segmental racks 13 13 and pinions 14 14, as before explained. These racks and pinions also hold the conveyer-trough at any desired elevation without the use of any catch or fastening. It will be seen that the upper ends of the segmental racks 13 13 are firmly secured to the sides of the conveyer-trough, and are so arranged that their toothed upper surfaces will always be held to mesh with the pinions 14 14 by means of the flanged guide-lugs 12 12, on which the lower ends of the racks are supported when the conveyer-trough is elevated. When the stacker is lowered and folded for transportation, as shown in Fig. 2, the racks 13 13 rest on lugs 42 42, secured to the sides of the main frame. By turning the crank 19 in one direction the shaft 15, with its gear 17 and pinions 14 14, will be actuated so as to move the segmental racks 13 13, and thereby elevate the stacker to any desired height. The lowering of the stacker is accomplished by simply reversing the move-

ment of the crank. When the stacker is elevated and extended, it can be readily turned horizontally to any desired angle with the main frame without disturbing the operative mechanism of the straw-carrier or conveyer-apron. This results from the flexible connection or gearing of the shafts 26 and 31, as before explained. In whatever direction the stacker may be turned it will be securely braced and held from accidental movement by the friction-clamp 38 and its connections, as well as by the dog 39 and brace 41, hereinbefore described.

After the conveyer-trough has been lowered and folded the pivotal gear-frame 4 may be tilted by throwing back the dog 39 and use of the crank so as to throw the king-bolt 6, bolster 9, and arms 10 10 backward, thereby affording a support for the forward or pivoted end of the conveyer-trough, reducing the height of the load, the rear end of which is now supported by a cross-bar, 43, attached to the standards 44 at the rear end of the truck, as shown in Fig. 2. In this condition the stacker is ready for transportation.

What I claim is—

1. The combination, in a straw-stacker, of a pivoted conveyer-trough, a pivoted bolster having arms for supporting one end of said trough, a shaft mounted in bearings on said bolster and having a worm-gear and pinions, and segmental racks secured to the opposite sides of the conveyer-trough and meshing with said pinions, whereby the conveyer-trough is raised or lowered and held at any required elevation or angle, substantially as described.

2. The combination, with a vertically and laterally movable conveyer-trough, of a tilting gear-frame, a king-bolt mounted therein, a bolster centrally pivoted on the upper end of said king-bolt and having arms adapted to support the pivoted end of the conveyer-trough, a shaft mounted in bearings on the under side of the bolster and geared at one end with the driving-roller of the conveyer-apron, a flexibly-gearred connection at its other end, a transmitting-shaft mounted in fixed bearings, and means for rotating the latter shaft, substantially as described.

3. The combination, with a vertically and laterally movable conveyer-trough, of a centrally-pivoted bolster having arms for supporting the pivoted end of said trough, a flanged ring adapted to serve as a brace and brake, a friction clamp or shoe movable on said ring, and adjustable chains connecting said friction-clamp to the bolster-arms, substantially as described.

4. The combination of a main frame having a fixed brace, as 41, and a movable dog, as 39, a tilting gear-frame pivoted to said main frame and provided with a beveled shoulder, 40, a king-bolt mounted in said tilting gear-frame, a bolster centrally pivoted to the upper end of the king-bolt and having an arm at each end, and a conveyer-trough pivoted to the bolster-arms, substantially as described.

5. The combination of a wheeled frame, a tilting gear-frame pivoted thereto and supporting a driving-shaft with pulley and sprocket-gear, a king-bolt mounted in said gear-frame, a bolster centrally pivoted to the upper end of the king-bolt and having arms at its ends, a conveyer-trough pivoted to the bolster-arms, a ring mounted on the wheeled frame and having a friction-clamp connected by adjustable chains to the bolster-arms, a shaft mounted in bearings on the fixed ring and gearing with the driving-shaft, and another shaft mounted in bearings on the pivoted bolster and having a flexible geared connection at its inner end with the shaft that is mounted on the ring, and carrying at its outer end a sprocket-wheel that is geared with a sprocket-wheel on the driving-roller of the conveyer-apron, substantially as described.
- 10 6. The combination, with the pivoted conveyer-trough 11, having segment-racks 13 13, of the swinging bolster 9, having arms 10 10, provided with flanged guide-lugs 12 12, the shaft 15, mounted in bearings on the bolster 25 and provided with a spur-gear 17 and pinions 14 14, and the worm-shaft 18 and crank 19, substantially as described.
- 15 7. The combination, with the pivoted bolster 9, having arms 10 10 for supporting one end 30 of the conveyer-trough, of the flanged ring 7,
- friction-clamp 38, and the adjustable chains 37 37 for connecting said clamp with the bolster-arms, substantially as described.
8. The combination, with the vertically and laterally movable conveyer-trough 11 and the centrally-pivoted bolster 9, having arms 10 35 10, supporting one end of said trough, of a shaft, 26, mounted in bearings on the pivoted bolster and having a pinion, 28, and a sprocket-wheel geared with the driving-roller of the 40 conveyer-apron, the loose bevel-gear 29, and the shaft 31, having a pinion 30, and a sprocket-wheel geared with the driving-shaft 5, substantially as described.
9. The combination of the wheeled frame 1, 45 the tilting gear-frame 4, pivoted thereto, the king-bolt 6, mounted in said gear-frame, the bolster 9, centrally pivoted to the upper end of the king-bolt and having arms 10 10, supporting the conveyer-trough, the dog 39, and 50 brace 41 for securing the extended conveyer-trough in working position, substantially as described.

In testimony whereof I affix my signature in presence of two witnesses.
